UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF NEW BRITAIN, CONNECTICUT, A CORPORATION OF CONNECTICUT.

LOCK AND LATCH.

SPECIFICATION forming part of Letters Patent No. 757,529, dated April 19, 1904.

Application filed January 19, 1904. Serial No. 189,666. (No model.)

To all whom it may concern:

Be it known that I, HENRY G. VOIGHT, a citizen of the United States, residing at New Britain, in the county of Hartford, State of Connecticut, have invented certain new and useful Improvements in Locks and Latches, of which the following is a full, clear, and exact description.

My invention relates to improvements in locks and latches, the object thereof being simplicity and economy of construction and effectiveness and durability in operation. In accomplishing this object I have been able to produce a structure which contains comparatively few operative parts, and those parts are so arranged and assembled that disorganization is well-nigh impossible.

In the drawings, Figure 1 is a plan view of my improved lock, part thereof being shown in section. Fig. 2 is an elevation of the inside of the uppermost section shown in Fig. 1. Fig. 3 is a horizontal section of the parts shown in Fig. 2. Fig. 4 is a vertical section of all the parts on the plane of the line 4 4, Fig. 2. Fig. 5 is a view taken on the section-line 5 5, Fig. 3, and looking in the direction of the arrows. Fig. 6 is a view taken on the section-line 6 6, Fig. 3, and looking in the direction of the arrows.

1 2 are escutcheon-plates.

3 4 are knobs, the shanks of which are mounted in any suitable manner on the plates 1 2, respectively.

5 is a latch bolt or head which in the form shown is pivoted at 51 on an end plate 6.

61 is a removable extension of the plate 6, said extension being designed to fill the space between the end plate 6 and the escutcheon-plate 1 in case of a wide adjustment of the plates 1 and 2. This lock is adapted to be inserted in a notch cut in the stile of a door, and the parts thereof are so arranged that they may be adjusted to doors of different thicknesses.

45 By means of the removable end plate 61 the escutcheon-plates 1 and 2 may be spread apart very considerably and the lock applied to a door of very substantial thickness. To effect

this separation or adjustment of the plates 1 2, I have provided a slidable connection which is more fully described in my former applications, Serial Nos. 185,207 and 185,208; but, briefly considered, it comprises slidably-arranged extensions 1^a and 2^a, secured to the plates 1 and 2, respectively, and by means of which the said plates are firmly held in parallel positions, but allowing said plates, nevertheless, to slide to and fro so much as may be necessary to secure any desired adjustment of spacing. The removable plate 61 has an extension 61^a, which lies to the rear of the face-plate 6 and between it and the extension 1^a. A pin 61^b on the inside of the end plate 6 registers with a hole or recess in this extension 61^a of the plate 61. When the parts are assembled, the extension 61^a fills the space aforesaid, and consequently prevents the tilting of the plate 61, and the pin 61^b prevents said plate from total disengagement.

The latch-controlling mechanism comprises a single slide 7, which is guided in a recess or cavity in the inner wall of one of the escutcheon-plates—for example, the plate 2. The forward end of the plate 7 is bent inwardly and hooked, as at 71, to engage a pin 52 on the latch bolt or head 5. The retractive action of the latch bolt or head 5 is effected by drawing back the slide 7 in the manner hereinafter described. 8 is what is termed an "easy-spring." This spring is mounted on pin 81, and one end of it bears against the back of the latch 5, normally pressing the latch outwardly into its operative position. There is a space in the back of the latch-bolt 5 forward of the hooked end of the slide 7 of sufficient size to permit the latch bolt or head to be pushed back independently of the slide 7—as, for example, when the door is being closed and the bolt or head of the lock encounters the strike-plate. (Not shown.)

The mechanism for operating the latch-slide comprises a spring 9, which may be mounted on the inner recessed wall of the escutcheon-plate 2, the free end of the spring bearing against the slide 7 to normally press it forward. The means for retracting the latch-

slide 7 comprises a roll-back 10, which has the usual projecting arms arranged to engage shoulders 72 72 of the latch-slide 7. The roll-back 10 is carried in the usual manner in 5 notches in the inner end of the outer knob-shank 41, so that when the outer knob is rotated it will, through the medium of the roll-back, retract the slide 7 and with it the latch bolt or head 5. The connection for the inner 10 knob with the latch-slide comprises a removable spindle 11, which is irregular in cross-section and arranged to take into a corresponding recess or cavity in the knob 3. The opposite end of the spindle 11 is reduced in 15 size and forms an irregular projection 11^a, which enters a corresponding pocket 12^a in the second roll-back 12. This second roll-back 12 has a round hub 12^b and a projection 12^c at the end thereof, which takes into a 20 similar opening in the hub 13 of a lock 14, which lock is preferably of the cylinder type and mounted in the knob 4. This second roll-back 12 has the usual arms adapted to engage the shoulders 72 72 of the latch-slide 7. 25 From the foregoing it will be apparent that when the inner knob 3 is rotated the spindle 11 will rotate and that this spindle will in turn rotate the roll-back 12, and thus retract the latch-slide 7. This rotation of the roll-back 12 is entirely independent of the roll-back 10. It thus appears that while the knobs 3 4 are arranged in line they are entirely independent and operate independently the single latch-slide 7. The knobs are independently rotatable, because the rotation of the spindle 11 by knob 3 does not rotate knob 4, or vice versa. It is true that the rotation of the spindle 11 will rotate the roll-back 12, but the squared extremity 12^c of the roll-back 40 hub 12^b may take a loose fit in the cap of the cylinder-plug, as best seen in Fig. 6. This loose fit will permit the said roll-back 12 to rotate to a sufficient extent to retract the slide without rotating the hub or plug of the lock 14. When the outer knob 4 is locked against rotation and it is desired to unlock the door from the outside, a proper key inserted in the cylinder-lock will permit the cap to be rotated to a point where it engages with the squared 45 extremity 12^c of the roll-back hub 12^b. A further movement of the key will thereupon rotate or rock the roll-back and retract the slide. Since the lock is adjustable to and fro, I deem it advisable to provide a means which 50 will normally press the spindle 11 into engagement with the roll-back 12, so that accidental disengagement of these parts may be prevented. This I accomplish in a simple and effective manner by means of a spring 11^b, carried 55 at the end of the spindle 11 within the knob 3. If desired, a pin 31 may be fixed within the knob 3 to center the spring 11^b. Any well-known means may be used in securing the knobs to the escutcheon-plates 1 2, so that 60 the knobs will take their bearings therein, be

supported thereby, and freely rotate therein. In the preferred form the knob 3 is secured by what is termed in the trade a "screwless" connection. This may comprise a divided knob-shank clamped together by a collar 32, 70 which overhangs one section of the knob-shank and screws on the other section of the knob-shank. This will be seen most clearly in Fig. 4. As these screwless knob-shanks are well known, further detailed description is deemed 75 unnecessary. One advantage of providing a screwless knob-shank for the knob 3 is that should the user desire to apply the lock to the door without separating the escutcheon-plates 1 2 and the associated parts he may do so 80 by removing the knob 3 and withdrawing the spindle 11, the usual adjusting-screws 15 15 being removable at any time. When this mode of operation is pursued, a small notch is cut 85 in the stile of the door sufficient to receive those parts of the lock closely adjacent to the end plate 6. The usual holes may be then bored through the door to receive the screws 15 15. A hole in line with the final position of the spindle 11 should also be bored. The 90 door is then ready for the lock. When the plates 1 and 2 are adjusted in place, the spindle 11 may be inserted through the passage in the still-attached connection of the outer knob-shank, thence through the hole in the door and 95 into the roll-back 12. The inner knob 3 may then be attached by means of the collar 32. The parts of the lock immediately to the rear of the face-plate 6, and to receive which the notch is cut in the stile of a door, may include 100 a locking device by which the outer knob may be locked against rotation. This locking mechanism may be controlled by a thumb-turn 16, accessible on the inner side of the door. 16^a is a spindle for said thumb-turn. This spindle takes into a hub 17, mounted in any convenient way close to the rear of the face-plate 6. 105 The operation of this latch mechanism may best be seen in Fig. 5. The inner end of the hub 17 may carry a pin 17^a, which projects into a slot 18^a on the bolt 18. By rotating the hub 17 the bolt 18 will slide to and fro. In the position shown in solid lines, Fig. 5, this bolt 18 is retracted. In the position shown in dotted lines this bolt 18 is advanced to its locking position, in which, it will be seen, said bolt engages a third arm 10^a of the roll-back 10, preventing rotation. Since the roll-back 11 is carried by the knob 4, it is obvious that 110 if the roll-back cannot be rotated the knob 4 cannot, and hence the latch 5 cannot be retracted from the outside by this means. To provide a means, however, for unlocking the door from the outside under such conditions, 115 the cylinder-lock is availed of. When a suitable key is inserted, the operative parts of the lock 14 may be turned or rotated independently of the knob 4, which rotation will, 120 by reason of the engagement between the 125

lock-hub 13 and the roll-back 12, cause the latter to be rotated, and hence cause the latch-slide 7 and latch-bolt to be retracted.

A simple means for holding all of the parts 5 in place at the inner side of the escutcheon-plate 2 may comprise a clip 19, which in operation may engage shoulders 20 20 on the inner side of the escutcheon-plate 2, the body of said clip overstanding the two roll-backs 10 of the latch-slide, securing them against accidental displacement.

21 is a spring which may press against the flattened portion of the hub 17 to frictionally hold it in the position indicated in solid lines, 15 wherein the outer knob is free to be turned, or in the position indicated by dotted lines, wherein the outer knob is locked against rotation.

It is obvious from the arrangement of the 20 parts of this lock that in applying it to a door a minimum amount of cutting the stile is possible. For example, the carpenter may cut a notch in the stile only to a depth sufficient to receive the spindle 16^a and hub 17 and may 25 bore a hole transversely through the door to receive the spindle 11, which spindle may be inserted after the lock has been applied by passing the same through the knob-shank of the knob 3, the latter being removed to permit 30 of said introduction of said spindle. Of course if it is immaterial whether the door is more deeply notched than just referred to the said notch might be cut back far enough to receive the spindle 11, which would obviate the 35 necessity of introducing the spindle after the lock is in place.

It will be observed that an important advantage of providing the removable extension-plate 61 resides in the fact that when the 40 thickness of the door to which the lock is to be applied is ascertained an extension-plate of suitable length, the end of which will not overstand the surface of the inside plate 1, may be applied. Stock doors vary in thickness 45 by quarters of inches. Hence these extension-plates 61 may be made of standard sizes varying by this fraction of an inch, and a suitable extension-plate may be inserted, so as to cover the forward edge of plate 1, but not 50 overstand the surface of the same. The parts when thus assembled and applied to the door would present the appearance indicated in Fig. 1.

What I claim is—

55 1. In a device of the character described, two plates arranged to be secured to opposite sides of a door, a knob carried by each of said plates said knobs being in alinement, a latch-slide carried by one of said plates, two roll-backs coacting with said slide, one of said roll-backs being operated by one of said knobs the other roll-back being operated by the other knob.

2. In a device of the character described, 60 two plates arranged to be secured to opposite

sides of a door, a knob carried by each of said plates, said knobs being in alinement, a latch-slide carried by one of said plates, two roll-backs coacting with said slide, one of said roll-backs being operated by one of said knobs 70 the other roll-back being operated by the other knob, said roll-backs being concentrically rotatable.

3. In a device of the character described, 75 two plates arranged to be secured to opposite sides of a door, a knob carried by each of said plates said knobs being in alinement, a latch-slide carried by one of said plates, two roll-backs coacting with said slide, one of said roll-backs being operated by one of said knobs 80 the other roll-back being operated by the other knob, one of said roll-backs being mounted to rotate in the other roll-back.

4. In a device of the character described, 85 two plates arranged to be secured to opposite sides of a door, a knob carried by each of said plates said knobs being in alinement, a latch-slide carried by one of said plates, two roll-backs coacting with said slide, one of said roll-backs being operated by one of said knobs 90 the other roll-back being operated by the other knob, and means to lock one of the knobs against rotation, and a key-controlled mechanism located on the same side as said locked knob for retracting said latch-slide independently of either knob.

5. In a device of the character described, 100 two plates arranged to be secured to opposite sides of a door, a knob carried by each of said plates said knobs being in alinement, a latch-slide carried by one of said plates, two roll-backs coacting with said slide, one of said roll-backs being operated by one of said knobs the other roll-back being operated by the other knob, and means to lock one of the 105 knobs against rotation, and a key-controlled mechanism located on the same side as said locked knob for retracting said latch-slide independently of either knob, said key-controlled means coacting with the roll-back 110 which is actuated by the unlocked knob.

6. In a device of the character described, 115 two adjustably-connected plates arranged to be secured to opposite sides of a door, a knob carried by each of said plates said knobs being in alinement, a latch-slide carried by one of said plates, two roll-backs coacting with said slide, one of said roll-backs being operated by one of said knobs the other roll-back being operated by the other knob, the means 120 of connection between one knob and one roll-back being adjustable.

7. In a device of the character described, 125 two plates arranged to be secured to opposite sides of a door, a knob carried by each of said plates said knobs being in alinement, a latch-slide carried by one of said plates, two roll-backs coacting with said slide, one of said roll-backs being operated by one of said knobs the other roll-back being operated by 130

the other knob, and means to engage one of said roll-backs and lock one of the knobs against rotation, and a key-controlled mechanism located on the same side as said locked 5 knob for retracting said latch-slide independently of either knob.

8. In a device of the character described, two plates arranged to be secured to opposite sides of a door, a knob carried by each of said 10 plates, a spindle spanning the space between and in line with both of said knobs, a latch-slide carried by one of said plates, two roll-backs coacting with said slide, one of said roll-backs being operated by one of said knobs 15 the other roll-back being operated by the other knob.

9. In a device of the character described, a plate arranged to be fitted to the outside of a door, another plate arranged to be fitted to 20 the inside of a door, a knob carried by each of said plates, a spindle spanning the space between said knobs and in line therewith one of said plates carrying complete latch-operating mechanism arranged on one side of the door 25 and covered by said plate, a latch, the said parts being so arranged that the space between said knobs may be varied without disconnecting either knob from said spindle.

10. In a device of the character described, 30 two plates, a knob carried by each plate said knobs being in alinement, a latch-slide carried by one of said plates, two independently-rotatable roll-backs carried by the same plate and coacting with said slide, means of connection between one knob and one of said roll-backs and an extensible extension between the other knob and the other roll-back whereby said plates may be applied to doors of different thicknesses without disconnecting either 40 knob from said roll-backs.

11. In a device of the character described, a pair of plates adjustably connected at one end whereby said plates may be moved toward or away from each other but are held in parallelism, a latch-slide carried by one of said plates, a latch bolt or head adjacent to the connection between said plates, two roll-backs carried by one of the plates and coacting with the slide and arranged to operate the same independently, one of said roll-backs being connected with one knob, the other roll-back being connected with the other knob through the slidable and rotatable spindle, and means to yieldingly press said spindle into operative 55 relation with its roll-back.

12. In a device of the character described, a pair of plates adjustably secured together at one end, a knob carried by each plate, a cylinder-lock carried by one of said knobs, a 60 spindle spanning the space between said knobs, said spindle making a connection with said cylinder-lock and at one end and with the op-

posite knob at the other end, one of said connections being slidable whereby the plates and knobs may be adjusted to and fro without disconnecting the spindle. 65

13. In a device of the character described, two plates arranged to be placed on opposite sides of a door, a knob carried by each plate, a roll-back carried by one of said knobs, a 70 second roll-back connected with the other knob said connection comprising a spindle said roll-backs being concentric, one of said roll-backs having a hub passing through the other roll-back, a key-operating means arranged within the first-mentioned knob and connected with said last-mentioned roll-back whereby one of the roll-backs may be rotated from either side of the door and means for locking against rotation the knob containing 75 the key-controlled mechanism, a latch bolt or head and a latch-slide connected therewith and arranged to be engaged by both of said roll-backs.

14. In a device of the character described, 80 a pair of side plates adjustably connected to each other at one end said adjustable connection including an end plate carried by one of said side plates and an extension-piece detachably connected to said end plate and arranged to overlie the adjacent edge of the opposite side plate, and means for holding said extension-piece in place when the parts are 85 assembled. 90

15. In a device of the character described, 95 a pair of side plates adjustably connected to each other at one end said adjustable connection including an end plate carried by one of said side plates and an extension-piece detachably connected to said end plate and arranged to overlie the adjacent edge of the opposite side plate, and means for holding said extension-piece in place when the parts are 100 assembled, said extension lying flush on its outer surface with the face of said face-plate. 105

16. In a device of the character described, 110 a pair of side plates adjustably connected to each other at one end said adjustable connection including an end plate carried by one of said side plates and an extension-piece detachably connected to said end plate and arranged to overlie the adjacent edge of the opposite side plate, and means for holding said extension-piece in place when the parts are 115 assembled, said extension lying flush on its outer surface with the face of said face-plate and overlying said face-plate on its inner surface.

Signed at New Britain, Connecticut, this 14th day of January, 1904.

HENRY G. VOIGHT.
